UNITED STATES PATENT OFFICE.

FRANK E. MORGAN, OF NEW HAVEN, AND JOHN A. EVARTS, OF WEST MERIDEN, ASSIGNORS TO THE BRADLEY & HUBBARD MANUFACTURING COMPANY, OF WEST MERIDEN, AND JEROME & CO., OF NEW HAVEN, CONNECTICUT.

TABLE-CLOCK.

SPECIFICATION forming part of Letters Patent No. 283,537, dated October 19, 1880.

Application filed September 6, 1880. (Model.)

To all whom it may concern:

Be it known that we, FRANK E. MORGAN, of New Haven, and JOHN A. EVARTS, of West Meriden, in the county of New Haven and State of Connecticut, have invented a new Table-Clock; and we do hereby declare the following, when taken in connection with the accompanying drawings and the letters of reference marked thereon, to be a full, clear, and exact description of the same, and which said drawings constitute part of this specification, and represent, in—

Figure 1, a front view. Figs. 2 and 3 illustrate the method of attachment.

This invention relates to an improvement in the method of attaching clocks to inkstands and other articles of table-furniture.

In the usual construction the clocks are made as a fixed and permanent part of the inkstand and other articles of furniture, and the clock is constructed to be wound at the rear. As considerable power is necessary to wind the clock, and the inkstand or other article of furniture must be firmly held during the operation of winding, it frequently occurs that the article to which the clock is attached is upset, broken, or otherwise disarranged by the operation of winding.

The object of this invention is to overcome this difficulty; and it consists in the construction as hereinafter described, and particularly recited in the claim.

In the illustration the clock is shown as applied to the pen-rack of an inkstand-support. On the bottom of the clock-case A a fork-shaped piece, *a*, is attached, and on the pen-rack a headed stud, *b*, is arranged, on which the fork-shaped piece is set, as seen in Fig. 3. The body of the case rests on a suitable seat formed on the rack. The head of the stud *b* on one side the fork and the rack on the oppo-

site side hold the clock in place, but from which it may be easily lifted and taken in hand for the purpose of winding, thus relieving the rack of the strain which would otherwise come upon it by the act of winding. The entire removal of the clock also avoids the necessity of in any way moving or disarranging the pen-rack or any parts to which it may be attached.

Instead of the fork-piece *a* on the clock and the headed stud on the rack, this order may be reversed—the stud arranged upon the clock-case and a corresponding slot in the pen-rack; or it may be simply a tongue under one and a loop on the other, into which the tongue will pass.

The illustration here given of the attachment of the clock to the pen-rack of the inkstand-support will be sufficient to enable those skilled in the art to attach the clock to other articles of table-furniture. Therefore, without confining ourselves to a specific method of attaching the clock to the article of table-furniture, or to any particular article to which the clock may be attached,

We claim—

The combination of a clock with articles of table-furniture, the case of the clock and the said article provided with means, substantially such as described, for removably attaching the clock to the said article, substantially as specified.

F. E. MORGAN.
JOHN A. EVARTS.
